UNITED STATES PATENT OFFICE.

JAKAB SKANDORA, OF FLINT, MICHIGAN.

DESIGN FOR AN AUTOMOBILE-RADIATOR.

50,488.

Specification for Design.

Patented Mar. 20, 1917.

Application filed January 3, 1917. Serial No. 140,462. Term of patent 7 years.

To all whom it may concern:

Be it known that I, JAKAB SKANDORA, a subject of the King of Hungary, residing at Flint, in the county of Genesee and State of Michigan, have invented a new, original, and ornamental Design for an Automobile-Radiator, of which the following is a specification, reference being had to the accompanying drawing, forming part thereof.

The figure is a view in front elevation, showing my new design.

I claim:

The ornamental design for an automobile radiator, as shown.

JAKAB SKANDORA.

Witnesses:

MAT TARAC,

BERT C. MOODY.
